United States Patent Office

Des. 190,653

Patented June 20, 1961

190,653

DESK

John A. Borden, 321 Camino Real W., Apt. 201,
Boca Raton, Fla.

Filed July 28, 1960, Ser. No. 61,554

Term of patent 14 years

(Cl. D33—7)

FIG. 1.

FIG. 2.

FIG. 3.

FIG. 4.

The dominant portions of my design are shown in full lines on the drawings.

I claim:

The ornamental design for a desk, as shown and described.
